CAR END INTERLOCK

John P. Gallagher, Jersey City, N. J., assignor, by
mesne assignments, to Standard Railway
Equipment Manufacturing Company, a corpora-
tion of Delaware

Application November 13, 1937, Serial No. 174,332

1 Claim. (Cl. 105—410)

Thre invention relates in general to a car end and specifically relates to a part of the car end which provides an interlock for securing a pressed steel car end to the car side. Differently identified, the invention relates to the providing of a rugged structural part of the end plate for securing the same to the side plate at each upper corner of the car end.

The primary object of the invention is to provide a simplified, permanent, and more rugged construction at the four upper corners of a car construction than is provided by known constructions.

Another object of the invention is to provide an improved technique in fabricating car ends which will insure the subsequent accurate interfitting of the car end with its associated parts of the balance of the car structure, particularly with the side plates, while avoiding the present practice of forcing distorted parts of the side plates, end plates and roof to fit each other at the time these component units are assembled.

It is the present practice in manufacturing steel cars of the box and similar type, to preform large sectional units as accurately as possible to their prescribed dimensions. Usually, the underframe is first formed, then the car sides are swung into their upright position secured to the underframe, then the car ends are swung into position with their corner post flanges disposed to the outside of the side plates and the end plate flanges of the car ends located between the side plates and finally the roof, as a unit is fitted over the open top box thus formed, as a tin can-cover is fitted over its can. In actual practice, the assembly operation is not always so simple. The element which gives the most trouble is the pre-formed pressed steel car end. It is the intermediate member in the assembly between the car sides and the roof and it must in turn fit the car sides and the roof must fit it.

It has been suggested heretofore that opposite ends of the end plate flange be secured to the two side plates forming the upper elements of the car sides. For this purpose opposite ends of the end plate flange at the upper edge of the end plates of the car are downturned to provide an upstanding plate herein identified as a side plate flange which is riveted to the side plates.

When the step is reached in the assembly line to secure such known forms of car end to the side plates, it quite frequently happens that one or both of these down-turned side plate flanges are not in the right position to fit snugly against

their companion side plate. This is due to numerous causes.

Another factor which has heretofore contributed to the difficulty of such snug assembly of car end, side plates and roof is that the car ends are formed and stacked ready for feeding to the assembly line as needed. The side plate flange being simply a bent lip of not very extensive dimensions, is very easily bent out of its initially formed position between the time of its formation and the installation of the car end in its final position, and when such a bent flange reaches the assembly line it is the usual practice of the assembly-man to hammer the flange back in position as best he can by means of sledge hammer blows. This resetting of the flanges back into their initial position is crude as the assembly-man has no way of telling just where the flange should be located and dependence must be made upon the subsequent riveting operation in securing the flange to the side plate to more or less fix the parts in their intended relation. The most serious objection to this practice, however, is that time is consumed in the interfitting of the parts on the assembly line. This practice seriously interferes with what would otherwise be a speedy, constant, step-by-step progress of the work along the assembly line and results in delays along the entire line.

Accordingly, an object of the invention is to provide a car end in which the side plate flange element is permanently secured in the prefixed position in which it was formed at the time the car end is fabricated, and which flange will remain in its accurately located position through the assembly period and throughout the life of the car.

With known forms of steel box cars of the type under discussion, there is a tendency for the car sides to bulge outwardly under the influence of laterally shifting lading in the car. In conventional forms of such cars, the side plate is a Z-shaped angle bar, the inner upstanding flange of which is secured at opposite ends to the side plate flanges of the car ends and the outer depending flange of which is secured at its opposite ends to the corner post flanges of the car end and is also secured between the corner post flanges to the sheeting forming the car sides. Lateral pressure against the inner side of the car side sheeting tends to swing the lower edge of the side plate outwardly about the hinge provided between the side plate and the two end plate flanges thus distorting the car from its ini-

tial configuration and materially weakening the side plates.

Another object of the invention is to provide for a tying together of each end of the side plates 5 to the end plates each in spaced relation to this hinge line, and in this way prevent or at least tend to prevent the outward swinging or distorting movement of the lower edge of the side plates and incidentally to strengthen the car sides 10 against bulging outwardly under the impact of shiftable lading in the car and equally to resist any tendency of the lower edge of the side plates from swinging inwardly about this hinge line in the event of inwardly directed impact against 15 the outer sides of the car.

Broadly, this aspect of the invention is attained by tying the end of the side plate flange nearest the end plate directly to the end plate so that the side plate flange becomes in effect a fixed part 20 of the end plate irrespective as to whether the end plate flange is present or not. This may be attained in several ways as hereinafter explained in detail. For instance, it may be attained by forming a closed corner between the end plate, 25 the end plate flange and the side plate flange, and which corner may be either an integral part of these elements of the car end or it may be an initially separate gusset accurately located on the car end and welded or otherwise permanently 30 secured in its accurately set position as an incident of the fabrication of the car end.

In connection with the feature of accurately locating the gusset in position, the invention contemplates the utilization of a spacing jig 35 or similar pattern form utilizing some bolt holes or other structural parts of the car ends as a point of reference for setting the jig to bring the side plate flange of the gusset quickly and accurately into the position which it must eventually occupy in order to snugly engage its associated side plates in the finally completed structure.

Various other objects and advantages of the invention will be in part obvious from a consideration of the method features of the disclosure and from an inspection of the accompanying drawings and in part will be more fully set forth in the following particular description of one method of practicing the invention, and 45 the invention also consists in certain new and novel modifications of the preferred method and other features of construction and combination of parts hereinafter set forth and claimed.

In the accompanying drawings: 50
55 Fig. 1 is a plan view looking down upon one end of the car before the roof is in position and illustrating a car end constituting a preferred embodiment of the article aspect of the invention and illustrating a structure formed by practicing one of the method aspects of the present disclosure;

Fig. 2 is a view in end elevation of the upper portion of the left half of the car end shown in Fig. 1;

60 Fig. 3 is a perspective view of one of the corners such as the right corner of Fig. 1 and showing the connection between the car end of Figs. 1 and 2 and one of the side plates;

Fig. 4 is an exploded view of the parts shown 70 in Fig. 3 before the side plate is riveted to the car end;

Fig. 5 is an enlarged vertical transverse sectional view taken on the lines 5—5 of Figs. 1, 3 and 6;

75 Fig. 6 is a detail plan view constituting an en-

largement of the showing at one side of Fig. 1 and looking down upon the detailed showing of Fig. 5; and

Figs. 7 to 10 inclusive illustrate a modified 5 form of the closed corner construction illustrated in the preceding figures and features a corner gusset secured to the car end in accordance with another method aspect of the present disclosure to form an accurately located side plate flange; Fig. 7 is a view similar to Fig. 2 of the other half 10 of a car end showing the parts in end elevation and showing in the upper right hand corner the gusset feature of this modified form; Fig. 8 is a view similar to Fig. 3; Fig. 9 is an exploded view of the parts shown in Fig. 8 and also showing 15 the locating jig in position to locate the gusset; and Fig. 10 is a view similar to Fig. 5 taken on the line 10—10 of Fig. 8.

Referring to the common parts of both forms 20 of the disclosure, there is shown a pressed steel car end 10 with its usual corrugations or embossments 11 above which is the relatively flat area 12 commonly designated as the end plate. The upper edge of the end plate is flanged inwardly to provide an end plate flange 13 sometimes referred to as the roof flange. Opposite vertical edges of the car end are flanged conventionally to form corner post flanges 14 and 15. Also following conventional practices in this respect, the upper portions of the corner post 30 flanges are offset outwardly to accommodate a depending flange 16 of a Z-shaped side plate 17. Flange 15 is provided with rivet holes 18 for accommodating rivets 19 for securing the upper 35 ends of corner post flanges to the adjacent ends of the side plates. The upper outer edge of the end plate and the end plate flange are cut back from the adjacent corner post flange as shown in the several views. It is also conventional practice in forming the car ends to provide the same 40 with sets of bolt and rivet holes some of which are shown in Figs. 2 and 7 to accommodate accessories and attachments usually applied to the ends of cars. Reference will be made specifically to a pair of such holes 20 and 21 (assuming Figs. 45 2 and 7 to show a complete car end) eventually used to secure a running board bracket in place and holes such as 22 and 23 in Fig. 7 eventually used to secure the roof in place. In one form of 50 practicing the method of locating the gusset in place it was found convenient to utilize the centrally located holes 20 and 21 as measuring points from which to space both gussets.

Referring particularly to the novel feature of this disclosure, it may be noted that it has been 55 known heretofore to provide a down-turned extension from opposite ends of the end plate flange to form a side plate flange similar to the side plate flange 24 in Fig. 4, but having both of its short edges free, and usually with the edge nearest the end plate spaced from and thus disconnected from the end plate edge, corresponding to edge 25, at the inner side of the cut-away portion. In the prior devices, as in the present disclosure, the side plate flange 24 was secured to 60 the upstanding inner flange 26 of the side plate 17. As noted above in the old form of freely movable side face flanges, there was a tendency of this flange to swing outwardly about the hinge line 27 formed between the end plate flange 13 70 and the side plate flange 26. Structurally, the present disclosure distinguishes from the known structure by welding or otherwise securing edge 28 of flange 24 to edge 25 of the end plate by welding or otherwise forming the closed corner 75

herein featured. An obviously similar and perhaps slightly better procedure is to bend flange 24 from the plane of the end plate 12 and weld along its top edge to the end edge 29 of the end plate flange. It is also suggested that a more preferred practice be to form the closed corner as a die pressing operation as suggested in Figs. 1-6. By the use of the suitable dies the corner can be formed as closed corners are not conventionally formed in pressed metal constructions. In this preferred method flange 24 is formed coevally with the formation of the end plate flange 13 and the end plate 12. This is preferred to the cruder method above suggested of simply welding the edges as there can be obtained in the finished structure the accuracy of locating the flanges inherent in approved practices in steel die press operations.

Referring to the modified form of the invention disclosed in Figs. 7 to 10, it is understood that the car end is formed conventionally without any side face flange preferably with the edges 25 and 29 cut back a little further than usual. As a separate operation, there is formed a one-piece pressing 30 constituting a three-sided gusset of the closed corner type. This gusset includes a gusset plate 31 fashioned to fit under the adjacent end of the end plate flange 13 and otherwise conformed to permit an adjusting of the plate 31 in the direction lengthwise of the end plate flange to permit of an eventual welding of the plate to this flange. The gusset also includes two flanges extending approximately at right angles to each other to form a substantially rugged angle iron reinforced across its included angle by the gusset plate 31. One of these flanges is relatively long and constitutes the side plate flange of this form of the invention. The other flange 33 is relatively short and constitutes an abutment to fit against the inner side of the end plate just within the edge 25.

It is vitally necessary that the side plate flange 32 be accurately located on the end plate in order to insure a snug fitting of the end plate as a whole with opposite ends of the end plate flange between the upstanding inner flanges 26 of the two side plates at opposite sides of the car. For economic reasons these car ends cannot be custom made and any car end of a particular order passing through the plant must fit, and accurately fit, any car. This necessity for accurate fit of any car end to any car structure is also necessary to provide a replaced end in case of accident so that a new end can be substituted for a damaged end without necessity of employing special technical assistance to make the replacement. It is therefore necessary that every gusset must be in the same position on its associated car ends as every other corresponding gusset on every other car end. In order to locate the side plate flanges advantage is taken of the accurate locating of one or more of the bolt holes punched in the plate in the act of forming the car end and using some selected bolt or rivet holes as a point of reference to locate a measuring jig. For this purpose a form of jig is carefully prepared as a gusset locating instrument. In the showing in Fig. 9, the two bolt or rivet holes 22 and 23 are utilized to locate a jig 34 which, as illustrated, is simply an angle iron, one leg 35 of which abuts the end plate 32 and a pair of drift pins 36 and 37 are passed through the leg 35 and into the holes 22 and 23. The other leg 38 forms a stop, abutment or face flange which is exactly in the plane which will be subsequently occupied by the

upstanding flange 26 of the associated side plate 17. With the jig in this position as shown in Fig. 9, the gusset is moved forwardly from the position shown and is quickly located with its side face flange 32 engaging the inner side of leg 38 and its flange 33 engaging the rear side of the end plate. When so located the gusset plate 31 is welded to the end plate along the lines 39 and 40, see Figs. 8 and 10. The jig is then, of course, removed and a rivet 41 passed through rivet holes 23 and 42 secures flange 33 to the end plate. Rivet hole 42 may be slightly enlarged to compensate for any minute shifting of the same relative to the rivet hole 23 in locating the gusset in position. It will be appreciated that with the side plate flange thus permanently secured in place at the time of the formation of the balance of the car end, it will remain in its thus accurately located position even though the car ends may be knocked about in stacking them and in moving them to the assembly line.

These car ends are swung into position following conventional practices in this respect but with the assurance that there will be no necessity at this stage of the proceeding to sledge hammer the side plate flange 24 back into position or to distort any part of the side plate 12 or the corner post flange or the roof flange or any part of the roof in order to insure the necessary snugness of interfitting parts. The end plate is simply pushed into position, the rivets 43 located in the automatically aligned rivet holes 44 preformed in the side plate flange 32 and the holes 45 in the side plate. The parts are thus permanently fastened together without any necessity at the assembly line of doing anything more than locating the preformed parts and riveting or bolting the parts together.

The preformed roof is then lowered into position following conventional practices in this respect with the assurance that the open top box thus formed by the car sides and car ends will receive the roof with the snug engaging of parts desired in such car constructions.

In the finished car, when in service, the side plates 17 and thus at least to some extent the sidings of the car indicated at 47 in Fig. 1 are held from their previous tendency to bulge outwardly thus tending to preserve the car as a whole in its originally constructed configuration. Any tendency of the lower edge of flange 16 of the side plates 17 to swing outwardly is resisted at opposite ends thereof by the resistance to stretching of the entire mass of both of the end plates. Any tendencies of the roof, or the roof flange to bend outwardly, are resisted by the gusset effect of the side plate flange which tends to resist bending along the transverse edge 46. In general, the construction tends to prevent relative movement of the corner forming parts along all of the closed angles at 25, (Fig. 3), 27 and 46, so that the disclosure particularly features an extremely simple, easily manufactured and mutually interbracing and interlocking construction at the four upper corners of the car.

The disclosure particularly features the providing of the rugged angle 48 formed between the end plate flange 12 and the integral side plate flange shown at 24 in the Figs. 1-6 disclosure, or the gusset form of side plate flange 32 in the Figs. 7-10 disclosure. With angle 48 closed it is, of course, not possible for the side plate flange to become accidentally bent out of place.

While there have been shown, described and pointed out in the annexed claim, certain novel

features of the invention, it will be understood that various omissions, substitutions and changes in the form and details of the device illustrated and in its operation may be made by those skilled in the art without departing from the spirit of the invention.

I claim:

In a railway car having a side plate comprising a horizontal web and an upstanding inner part 10 and a depending outer part in combination with

an end wall sheet with the upper margin thereof bent to form a horizontal flange with one end thereof bent to form a depending flange which is secured to said upstanding part of the side plate, and means to secure one edge of said depending flange to the body of the end wall sheet, said wall sheet having a vertical margin thereof bent to form a lateral flange which is secured to said depending part of the side plate.

JOHN P. GALLAGHER. 10
